UNITED STATES PATENT OFFICE.

JOSEPH GILBERT CARRIER, OF CHICOUTIMI, QUEBEC, CANADA.

PULP-MACHINE.

1,344,173.

Specification of Letters Patent. Patented June 22, 1920.

Application filed April 5, 1919. Serial No. 287,810.

To all whom it may concern:

Be it known that I, JOSEPH GILEERT CARRIER, a subject of the King of Great Britain, residing at Chicoutimi, Province of Quebec, 5 Canada, have invented certain new and useful Improvements in Pulp-Machines; and I do hereby declare that the following is a full, clear, and exact description of the invention, such as will enable others skilled 10 in the art to which it appertains to make and use the same.

The present invention relates to pulp machines generally known as ground wood sulfite wet machines wherein the woodpulp is 15 conveyed on a suitable screen to collecting rollers. The woodpulp as it collects upon these rollers has to be severed therefrom and heretofore it has been severed by hand or automatically operating cutters, but such 20 devices have proven very unsatisfactory due to the fact that the laps or sheets of woodpulp are not cut in uniform length, or the cutting has been so inaccurate as to cause the collected sheets of woodpulp to be again 25 deposited on the screen where they repeated their gathering operation. This invention pertains more particularly to an attachment for such pulp machines whereby the woodpulp in the form of sheets may be automatically 30 severed and removed from the receiving roller of the machine when a pre-determined thickness of stock has been collected upon said receiving roller.

An object of the present invention is to 35 provide an improved attachment of this character which will automatically and effectively cut the woodpulp into sheets of pre-determined length and thickness.

Another object of the invention resides in 40 the provision of means for adjusting the blades and associated mechanisms, with respect to the pulp accumulating roller and providing for the positive return to normal position of the said mechanisms.

45 A still further object of the invention contemplates the simultaneous cutting of the accumulated pulp on the gathering roller and the continuous pulp sheet and uniting the severed pulp sheet with the 50 finished product after the cutting operation.

A further object of the present invention is to provide an attachment of this character which may be easily and readily applied to any pulp machine now in general 55 use and one which would be strong, durable

and efficient in use, and which would also be simple and accurate in operation.

With the above and other objects in view which will hereinafter appear as the description continues, the invention consists 60 of the novel features of construction, combination and formation of parts as will be hereinafter more fully described and particularly pointed out in the appended 65 claims.

In the accompanying drawings has been shown a simple and preferred form of the invention, it being, however, understood that no limitation is necessarily made to the precise structural details herein exhibited, 70 but the right is hereby reserved to any changes, alterations or modifications to which recourse may be had that come within the scope of the claims without departing from the spirit of the invention or 75 sacrificing the efficiency of the same.

In the accompanying drawings:

Figure 1 is a perspective view of the portion of the pulp machine having the invention applied thereto;

Fig. 2 is a vertical section through the same showing the position of the various members as the pulp is being collected upon the forming rollers;

Fig. 3 shows a similar view of the attachment being set in operation to sever the pulp where it is formed into sheets;

Fig. 4 is a detail perspective view of the attachment;

Fig. 5 is a detail sectional view of the connection between the attachment and the collecting roller;

Fig. 6 is a front elevation of the ratchet roller carried by the collecting roller;

Fig. 7 is a detail section through the 95 same;

Fig. 8 is a detail sectional view of an adjustable support for the attachment;

Fig. 9 is a fragmental front elevation of one of the severing blades;

Fig. 10 is a vertical section through the same;

Fig. 11 is a detail elevation of the other severing blade;

Fig. 12 is an end elevation of the same, 105 and showing a means for connecting same to the operative members of the attachment;

Fig. 13 is a detail side elevational view of a modified form of the oscillating connection between the attachment and the collect- 110

- ing roller with the mechanism in inoperative position;
- Fig. 14 is an end elevational view of the same;
- 5 Fig. 15 is a view similar to Fig. 13, with the mechanism in operative position;
- Fig. 16 is a frontal elevation of a modified form of one of the collecting roller operating elements;
- 10 Fig. 17 is a detail sectional view of same; and,
- Fig. 18 is a fragmental side elevation of operating mechanism for the secondary severing blade.
- 15 Referring now more particularly to the accompanying drawings wherein like and corresponding parts are designated by similar reference characters throughout the several views.
- 20 The pulp machine as illustrated in the drawings consists of a main frame comprising side supports 1 and 2 which are specifically connected by a plurality of bars, as shown, and which serve to brace the same, and mounted upon these frames 1 and 2 are the supplemental frames 3. Journaled within suitable bearings carried by the frames 1 and 2, is a felt roller 4 and arranged above this felt roller 4 and having contacting engagement therewith is a pulp collecting or receiving roller 5, provided with the laterally extending stub shafts 6. Also journaled within suitable bearings carried by the frames 1 and 2, are the idler rollers 7, over which passes a continuous felt conveyer 8. This felt conveyer extends over the idler 7, as well as the felt roller 4 and one portion thereof travels through a suitable collecting reservoir or screen, not shown, whereby the woodpulp contained within said reservoir is collected by this felt conveyer 8, in a thin sheet as indicated by the numeral 9, where it is conveyed between the rollers 4 and 5. As this continuous sheet of woodpulp is being fed between the rollers 4 and 5, it will be collected upon the periphery of the collecting roller 5. As this woodpulp is collected upon the receiving roller 5, its thickness will gradually increase until it has obtained a thickness as indicated by the numeral 10 in Fig. 3. Slidably mounted within oppositely disposed vertical channels in the frames 3, are the bearing blocks 11 on the upper surfaces of which are connected the lower ends of the coil springs 12 while the upper ends thereof are connected to the adjusting screws 13 which carry the handles 14. These bearing blocks 11 rest upon the stub shafts 6, so that the tension upon these stub shafts and consequently the receiving roller 5 may be regulated as desired. As thus far described the machine is substantially of the form now in general use.
- 65 As stated in the outset of the specifi-

tion, the invention relates to an improved attachment to be applied to such machines for the purpose of automatically severing the collected sheets of woodpulp which are of pre-determined thickness indicated by the numeral 10, and to cut these sheets when this pre-determined thickness has been obtained into pre-determined lengths. Journaled within a bearing 21 secured to the frame 3 in any suitable manner is a frame 75 consisting of a stationary section 15 and an adjustable section 16 which are connected through the slot and bolt connections 17, and an adjusting screw connection 18 is provided whereby the adjustment may be manually regulated to the degree desired. The upper end of the section 15 is provided with a bearing 19, having keyed therein one end of a shaft 20 and the opposite end of this shaft 20 is mounted within the bearing 21. 80 Rigidly connected to this shaft 20 are the sleeves 22, carrying a depending frame or knife holder 23. The lower end of this frame 23 is provided with an angular flange 24 and bolts or rivets 25 pass through apertures in this flange and a similar flange formed on the knife blade 26. This severing means or knife blade 26 is normally retained out of contact with the roller 6 during the accumulating period and is intermittently inoperative, but when the woodpulp attains a predetermined thickness upon this roller 5, the knife 26 is automatically set into operation, whereby the woodpulp will be severed and permitted to drop from the roller and rest upon a suitable table or support 27. Carried by one of the stub shafts 6 of the collection roller 5 is a pulley 28 having a parallel smooth flange 29, which is concentric with the shaft 6, and this parallel flange 29 is provided with a countersunk recess 30 in which is wedged a block 31, having segmental teeth 32 formed in the outer face thereof. This block 31 is likewise retained in position by means of one of the bolts 33 which latter serve to secure the pulleys 28 to the ends of the receiving roller 5. The lower end of the adjustable section 16 of the knife support is provided with an enlarged portion 34 having an alining opening 35 formed therein in which rests the pulley 28. Pivottally connected as at 36 to this enlarged portion 34, is an arm 37, having an enlarged outer free end 38 which acts as a weight so as to cause the lower face of this arm 37 to rest upon the outer periphery of the flange 29. The lower face of this arm 37 is provided with a series of ratchet teeth 39, which are adapted to engage the teeth 32 of the pulley 28. The smooth portion 40 of the lower face of this arm 39 rests upon the outer flange 29 of this pulley when the receiving roller 5 is in its lowermost position, but when the woodpulp accumulates upon the roller 5 and 130

its thickness increases, the roller 5 will be caused to rise and by carrying the pulley 28 therewith, the teeth 32 will be caused to engage the teeth 39 and thereby cause the 5 arm 37 to travel a short distance with the pulley 28. The pulley rotating in the direction of the arrow as shown in Fig. 4, will cause the arm 37 to travel in a rearward direction and this arm 37, will in turn cause 10 the frame 15 to move, thereby rocking the shaft 20 within the bearings 21. When the shaft 20 has been rocked it will cause the blade 26 to assume substantially the position shown in Fig. 3, where it will engage the 15 woodpulp upon the roller 5 and sever the same. The woodpulp after it has been carefully cut in the manner as shown in Fig. 3 will be divided substantially into two sections, the outer one of which, indicated by 20 the numeral 41, will drop due to its own weight upon the table 27, and the opposite section thereof indicated by the numeral 42 will travel between the rollers 4 and 5 and subsequently will be deposited upon the 25 table 27. By making the frame 15 of two adjustable sections it is obvious that the cutting blade 26 may be caused to swing into operative position when the various desired thicknesses of pulp have accumulated 30 upon the receiving roller 5. The desired thickness being pre-determined the section 15 of this frame may be adjusted to the right position so as to cause the blade 26 to be operated when this pre-determined 35 thickness of woodpulp has adhered to the roller 5. The continuous sheet of woodpulp indicated by the numeral 9 is fed to the collecting roller and when the woodpulp has been cut upon this roller, it is desirous to 40 cut the feeding sheet 9 at the same time, so as to only feed between the rollers 4 and 5 a sheet of woodpulp which will terminate with the end 42 of the woodpulp collected upon the receiving roller, whereby the sheet 45 of severed woodpulp will have the same thickness throughout its length. To cut this sheet 9 I have provided another cutting blade 43 and this blade 43 is secured within a frame 44 carried by a rocker shaft 45. 50 Suitably mounted upon the frames 3 are the rearwardly extending rods 46 and 47, each of which having secured thereto a bearing block 48, and journaled within these bearing blocks 48 is the rocker shaft 45. Carried by the rods 46 and 47 are the depending adjustable but rigidly held links 49, and slidably mounted within the links 49 carried by the rod 47 is a rod 50, and this rod 50 has connected thereto an adjustable block 51. Keyed to one end of this rocker shaft 45 is a sleeve 52 having a depending weight 54 which normally holds the cutting weight 43 in the position as shown in Fig. 2. Pivotally mounted upon the outer face of this 60 sleeve 52 is a pawl 55 having one end there- of adapted to project within the travel of the block 51 and its opposite end adapted to engage the projections 56 carried by the sleeve 52. When this block 51 travels in the direction of the arrow as shown in Fig. 4 it will strike against this pawl 55 and the pawl engaged in the projection 56, will cause the rocker shaft 45 to oscillate and cause the blade 43 to assume the position as better shown in Fig. 3 where it will sever the continuous sheet of woodpulp. Formed integral with the enlarged portion 34 of the frame 16, is a weight 57, which normally holds the frame 15 and the rocker shaft 20 in the position as better shown in Figs. 2 and 4, whereby the blade 26 will be held out of contact with the woodpulp and will always be caused to return to this normal or inoperative position. The rod 50 is connected to this weight 57 through a rod 58, so that when the frame 15 is caused to move, the rod 50 will also be carried therewith and in turn the blades 43 and 26 will be jointly set in operative position, whereby they will sever the woodpulp at the same time. Carried by each of the frames 3 are the brackets 59 and these brackets 59 have mounted therein a threaded rod 60. Adapted to travel upon this threaded rod 60 is a sleeve 61 of a bracket 62. The inner ends of the rods 46 and 47 may be retained within the sleeve 62 by means of the bolts 63, and by rotating the screw 60 the frame 62 as well as the rods 47 and 48 may be vertically adjusted so as to adjust the blade 43 to the desired height. The brackets 62 are provided with depending portions 54 and extending through the slots 65, formed within these depending portions 64, is a bolt 66 and this bolt 66 is in threaded engagement with the bracket 59. From this construction it is obvious that the brackets 62 may be adjusted and locked in this adjusted position by means of the bolts 66. 70 From the foregoing it will be obvious that the felt conveyer 8 will cause the woodpulp to be collected thereupon in a continuous sheet as indicated by the numeral 9 and this sheet of woodpulp is fed between the rollers 4 and 5 in the usual manner. The roller 4 75 may be connected with a suitable source of power so as to cause the same to revolve continuously in one direction, and as the receiving roller 5 frictionally engages the felt 8 it will also be caused to revolve. As the 80 woodpulp travels between the rollers 4 and 5 it will be collected upon the receiving roller 5. A pre-determined thickness of the woodpulp desired upon this receiving roller may be ascertained and the frame 16 may 85 be so adjusted that when this pre-determined thickness of woodpulp upon the roller 5 has been obtained, the severing mechanism will be set into operation. When the woodpulp has been collected upon 90

the roller 5 in this pre-determined thickness the roller 5 will be caused to raise, and in so raising the ratchet teeth 32 will be brought into engagement with the ratchet teeth of 5 the lever 39 of the lever 37, and as this roller 5 is continually rotating the lever 37 will be carried a short distance in a rearward direction with the pulley 28, thereby swinging the frame 15 and the rocker shaft 20 10 so that the blade 26 will engage the woodpulp upon the roller 5 for severing this woodpulp and forming a single sheet. When this frame 15 is moved into rearward direction the rod 50 will also be caused to 15 move in a rearward direction as it is connected to this frame 15 through the link 58. The block 51 will engage the pawl 55, and in turn the rocker shaft 45 will be oscillated so as to bring the blade 43 into cutting engagement with the woodpulp indicated by the numeral 9, thereby severing this continuous sheet of woodpulp so that the portion 42 from the woodpulp which has yet to pass through the rollers 4 and 5 will 20 receive this severed sheet 9 of woodpulp so that the section 42 after it has been passed between the rollers 4 and 5 will have the same thickness as the section 41. After this sheet 10 of woodpulp has passed between the rollers 4 and 5 and been deposited upon the table 27 the roller 5 will drop due to its own weight down upon the felt conveyer 8. When this roller 5 has been lowered the ratchet teeth 39 will be out of engagement with the ratchet teeth 32 by the pulley 28, and the weight 57 will cause the frame 15 and the blade 26 to return to its normal position. When the frame 15 has 35 returned to its normal position the bar 50 will be again drawn forward and a block 51 will be permitted to pass by the pivotally supported pawl 55. The weight 54 connected to the rocker shaft 45 will also cause the cutting blade 43 to return to its normal position. The pulp machine still being in 40 continuous operation will deliver the sheet 9 again between the rollers 4 and 5 wherein another supply of woodpulp may be accumulated upon the roller 5, and in this 45 manner the woodpulp may be continually fed to the collecting roller and the sheets 10 of woodpulp may be formed having a pre-determined thickness in all its length and a pre-determined length. 50

55 In the modifications illustrated in Figs. 13 to 18 inclusive, I have provided an actuating mechanism for blade 26 and the secondary cutting blade 43, embodying to a maximum degree, simplicity of construction and operation. This mechanism particularly illustrated in Figs. 13 and 14, comprises a stationary section 67 and an adjustable section 68 which are connected through oppositely disposed slot and bolt connec-

tions 69 and 70. The upper end of the stationary section 67 is provided with a bearing 71, having keyed therein one end of the shaft 20, while the opposite end is keyed in a similar bearing not illustrated, but positioned at the other side of the machine. 65

The stationary section 67 is provided with an integral outwardly projecting lug 72, which latter extends through and is capable of adjustment on a vertical plane in the central slot 73 of the section 68. Shoulders 74 70 are formed integral with section 68 and are provided with interiorly threaded apertures 75 adapted for reception of the screws 75. These screws 75 have their lower ends in permanent contacting engagement with the lug 72, so that, upon adjustment of same, the movable section 68 may be raised or lowered with respect to the stationary section 67. In this connection it is necessary only to unloosen the bolt 70, extending through the said sections. Mounted on the stub shaft 6, of the collection roller 5 is a pulley member 76, and the said member is adapted for the reciprocatory motion within the alining opening 77 in the enlarged lower portion of the adjustable section 68. The pulley 76 at its central part is provided with a short spindle 78 and a rocking member 79 is mounted thereon and adapted for limited movement with respect to the said pulley 76. 90 A casing 80 carrying double annular ball bearings is disposed between the spindle 78 and the rocking member 79 and a threaded bolt 81 takes into a recess in the spindle and serves to hold the said rocking member 79 95 thereon. The rocking member comprises two integrally formed segment shaped elements 82 and 83, and is adapted for movement on the outer flat surface of the pulley proper. The outer face of the pulley adjoining the periphery of the same is provided with a ring 84 which has its ends spaced apart to allow for a limited movement of the segment element 82 therebetween. The outer peripheral edge of the segmental element 82 is concentric with the axis of roller 5, so that upon the revolution of the roller the segmental element 82 is in 100 intermittent engagement with the downwardly bowed portion 85 of the adjustable section 68. 110

During this contacting engagement, the rocking member 79 is moved on its pivot and the segment element 82 travels in the ring space on the pulley face and therefore, 120 the stationary and adjustable sections 67 and 68 are rocked in unison. The degree of the rocking movement of the said sections depends upon the size of the opening between the ring ends. 115

A weight member 86 is attached to one side of the enlarged lower portion of the adjustable section 68, by bolts passing 125

through lugs 87 arranged on said sections and the said weight holds the frames and rocker shaft 20 in the position illustrated in Fig. 4, so that the blade will be held out of contact with the woodpulp and also cause the same to return to normal or inoperative position thereafter.

As in the preferred form the rod 88 is connected to the weight member 86 through a rod 89 and when the frames are caused to move the rod 88 will be carried therewith. A rod 90 extends in a parallel plane to the rod 88 and the same are connected together by depending adjustable links 91. Keyed to one end of the rocker shaft carrying the blade 43 not illustrated, is a sleeve 92 having a depending weight 93, which normally holds the blade 43 in position as illustrated in Fig. 4. A pawl member 94 is pivotally mounted upon the outer face of the sleeve 92 and has one face adapted to project within the travel of a block 95 on rod 88, and its opposite end to engage the projection 96 carried by the sleeve 92. When the block 95 travels in one direction it will strike against the pawl member 94 and the latter will cause the rocker shaft carrying the knife or blade 43 to oscillate and assume an upright or cutting position to sever the continuous sheet of woodpulp. The weight 93 is formed with horizontally extending arms 97 which are connected with the collars 98 by the coil springs 99, and the tension exerted by said springs serves to return the said weight member 93 to normal position from either direction. These collars 98 are adjustable on rod 90 to regulate the swing of the weight member 93. The rod 88 is adapted to be tensioned back to normal position by the coil springs 99, which encircle that portion of the said rod between one of the links 91 and a collar 100. The function of these springs is to exert sufficient energy to force the rod 89 downwardly against the weight member 86 and return the sections 67 and 68 to their normal positions.

For the purpose of adjusting the sections 67 and 68 in a horizontal plane with respect to the pulley member 76, to regulate the contacting engagement of the bowed portion 85 with the segment element 84, I provide a regulating member 101, comprising a split collar 102, formed with oppositely disposed flanges 103, which are apertured for a plurality of bolts 104. These bolts are screwed into apertured flanges 105, formed on the upper end of the stationary member 67, and in order to shift the above member on shaft 20, it is only necessary to unloosen the bolts 104 and a centrally disposed bolt 106 and withdraw the shaft key 107.

It is therefore seen that by this novel construction the main blade swinging elements are adjustable in vertical and horizontal

planes with respect to the pulley element 65 and means are provided for a more positive return to normal position of the actuating mechanism.

It is also apparent that this attachment will be automatically operated while the pulp machine is in continuous operation and that none of the woodpulp which is fed to the receiving rollers is wasted. The woodpulp after it has been formed in the sheets 10 of the same length and thickness 75 may then be presented to a suitable dehydrating press, where the water contained therein may be pressed from the sheets and the same suitably packed to be shipped to paper manufacturers.

Whereas in the drawings I have illustrated this attachment as applied to one side of the pulp machine, it is of course to be understood that this attachment may be applied on both sides of the machine, but have 85 a joint operation, so that the cutting blades 26 and 43 will operate in unison.

Having thus fully described my invention, what I claim as new and desire to secure by Letters Patent is:—

1. In a pulp machine of the character described having a collecting member, and means for feeding the continuous sheet of pulp to said collecting member, of means for cutting the pulp upon said collecting 95 member and said continuous sheet substantially as and in the manner specified.

2. The combination with a pulp machine having a collecting member and means for feeding a continuous sheet of pulp to said 100 collecting member, and means actuated by said collecting member, whereby the collected woodpulp and continuous pulp sheet will be severed substantially as and in the manner specified.

3. In a pulp machine of the character described the combination having a collecting member and means for supplying a continuous sheet of woodpulp to said collection member, of means for cutting the wood 110 pulp upon said collecting member and said continuously fed sheet of woodpulp, and means whereby said collecting member will jointly actuate said cutting means.

4. The combination with a pulp machine 115 having a collecting roller and means for supplying a continuous sheet of woodpulp to said collecting roller, of two cutting members for severing the woodpulp upon said collecting roller and said continuous sheet, 120 and means for automatically and jointly operating said cutting members.

5. The combination with a pulp machine having a pulp receiving roller, of two cutting blades for severing the pulp from said 125 roller and the continuous pulp sheet, and means operatively connecting said cutting blades with said roller, whereby when said

roller is raised the cutting blades will be operated.

6. The combination with a pulp machine having a receiving roller and means for supplying a continuous sheet of woodpulp to said roller, a cutting blade arranged above said roller, a rocker shaft for supporting said cutting blade, a second cutting blade, a rocker shaft for said blade, means for operatively working said rocker shafts with said roller, whereby said rocker shaft may be moved at pre-determined intervals for causing said cutting blades to sever the woodpulp upon said roller and said continuously fed sheet of woodpulp.

7. The combination with a pulp machine having a receiving roller and means for delivering a continuous sheet of woodpulp to said roller, a cutting blade arranged above said roller, means for operatively connecting said cutting blade with said roller, a cutting blade for severing the continuous sheet of pulp, and means whereby when a pre-determined thickness of woodpulp has been collected upon said roller said cutting blades will be brought into operation substantially as and for the purpose specified.

8. The combination with a pulp machine having a receiving roller and means for supplying woodpulp to said roller, of a rocker shaft journaled upon said machine, a cutting blade carried by said rocker shaft, a frame connected to said rocker shaft, said frame comprising two adjustable sections, and means for operatively connecting said adjustable frame to said roller, whereby said cutting blade may be operated at pre-determined intervals.

9. The combination with a pulp machine having a receiving roller and means for supplying woodpulp to said roller, of a rocker shaft journaled within said machine, a cutting blade carried by said shaft, a frame connected to said rockable shaft, of a rack carried by said frame, and means whereby said rack may be brought into operative connection with said collecting roller for operating said cutting blade substantially as and for the purpose set forth.

10. The combination with a pulp machine having a receiving roller and means for supplying woodpulp to said roller, a rockable shaft journaled within said frame, a cutting blade carried by said shaft, a frame carried by said shaft, a rack bar connected to said frame and means carried by said receiving roller whereby when the receiving roller is raised the said rack bar will be moved for rocking said shaft substantially as and for the purpose specified.

11. The combination with a pulp machine having a receiving roller and means for supplying woodpulp to said roller, of a rockable shaft, a cutting blade carried by said

shaft, a frame connected to said shaft, a rack carried by said receiving roller, and means whereby when said receiving roller is raised in a vertical direction said rack will engage said frame for rocking said shaft substantially as and for the purpose specified.

12. The combination with a pulp machine of the character described comprising a receiving roller and means for supplying woodpulp to said roller, of a rocker shaft journaled upon said machine, a pulp severing blade carried by said rocker shaft, a frame connected to said shaft, said frame comprising two adjustable sections, one of said sections having an opening therein, a pulley carried by said receiving roller and adapted to travel within said opening, a rack bar pivotally connected to said frame, a detachable rack block mounted within said pulley, means whereby when said receiving roller is moved in a vertical direction said rack block will engage said rack bar and said frame moved for rocking said shaft substantially as and for the purpose specified.

13. The combination with a pulp machine having a receiving roller and means for supplying a continuous sheet of woodpulp to said roller, a pair of cutting blades mounted upon said machine, and means for operatively connecting said cutting blades with said roller, whereby the cutting blades may be operated at pre-determined intervals.

14. The combination of a pulp machine having a receiving roller and means for supplying a continuous sheet of woodpulp to said roller, a cutting blade arranged upon said roller, a cutting blade arranged upon said sheet of woodpulp, means for jointly connecting said cutting blades, and means for operatively connecting said blades to said roller substantially as and for the purpose specified.

15. The combination with a pulp machine having a receiving roller and means for supplying a continuous sheet of woodpulp to said roller, cutting blades mounted upon said machine, one of said blades adapted for cutting the pulp upon said roller and the other of said blades adapted for cutting the continuous sheet of pulp, a frame pivotally mounted upon said machine for jointly operating said cutting blades, a weight for retaining said frame in normal position and means for automatically swinging said frame whereby the cutting blades will be brought into operation.

16. The combination of a pulp machine having a receiving roller and means for supplying a continuous sheet of woodpulp to said roller, a pair of cutting blades, a frame for jointly actuating said cutting blades, means for holding said cutting blades in one position and said receiving roller

- adapted to actuate said frame when a predetermined thickness of woodpulp has accumulated thereon, whereby the woodpulp upon said roller and the continuous sheet 5 may be simultaneously severed substantially as and for the purpose specified.
17. The combination with a pulp machine having a receiving roller and means for supplying a continuous sheet of woodpulp to 10 said roller, of a cutting blade adapted to engage said sheet of woodpulp, an adjustable frame mounted upon said machine, a rockable shaft connected to said cutting blade and mounted upon said adjustable 15 frame, a swinging frame, means for operatively connecting said swinging frame with said roller, and means whereby when said swinging frame is moved in one direction said cutting blade will be brought in cutting 20 engagement with said sheet of woodpulp upon said roller and the said continuous sheet substantially as and for the purpose specified.
18. The combination with a pulp machine 25 having a receiving roller and means for supplying woodpulp to said roller, of a rocker shaft journaled upon said machine, a cutting blade carried by said shaft, a frame connected to said rocker shaft, a frame operatively connected to said roller for intermittently rocking said shaft, means for 30 adjusting the cutting blade with respect to said roller, and means for adjusting said rocker shaft in a horizontal plane.
- 35 19. The combination with a pulp machine having a receiving roller and means for supplying woodpulp continuously to said roller, of a cutting blade arranged above said roller, a rockable shaft for supporting 40 said cutting blade, an adjustable frame connected to said shaft, means for intermittently actuating said rockable shaft, means

for adjusting said shaft in vertical and horizontal planes with respect to the receiving roller, and means for operatively connecting said frame with said roller. 45

20. The combination with a pulp machine having a receiving roller and means for delivering woodpulp to said roller, of a rocker shaft journaled upon said machine, a cutting blade carried by said shaft, a frame connected to said rocker shaft, means for supplying a continuous sheet of woodpulp to said collection roller, means for cutting the collected woodpulp upon said roller, 50 means for cutting the continuously fed sheet of woodpulp, and means for returning the cutting elements to normal position after the cutting operation.

21. The combination with a pulp machine 60 having a receiving roller and means for delivering woodpulp to said roller, means for supplying a continuous sheet of woodpulp to said collection roller, means for cutting the collected woodpulp upon said roller, 65 means for cutting the continuously fed sheet of woodpulp, and means for adjusting the said blades with respect to the feeding and collected felt.

22. The combination with a pulp machine 70 having a receiving roller and means for delivering woodpulp to said roller, means for supplying a continuous sheet of woodpulp to said roller, means for cutting the accumulated woodpulp, means for cutting the 75 continuously fed sheet of woodpulp, means for adjusting the said blade with respect to the said roller, and means for returning the cutting elements to normal position after the cutting operation. 80

In witness whereof I have hereunto set my hand.

JOSEPH GILBERT CARRIER.
